DESIGN FOR A COMBINED REFLECTOR AND PRISMATIC BOWL FOR LIGHTING FIX- TURES

Thomas W. Rolph, Newark, Ohio, and Henry L. Logan, New Rochelle, N. Y., assignors to Holophane Company, Inc., New York, N. Y., a corporation of Delaware

Application August 18, 1938, Serial No. 79,425

Term of patent 14 years

To all whom it may concern:

Be it known that we, Thomas W. Rolph and Henry L. Logan, citizens of the United States of America and residents, respectively of Newark, in the county of Licking and State of Ohio; and New Rochelle, in the county of Westchester and State of New York, have invented a new, original, and ornamental Design for a Combined Reflector and Prismatic Bowl for Lighting Fixtures, of which the following is a specification, reference being had to the accompanying drawing, forming a part thereof.

Figure 1 is a side elevational view of the combined reflector and prismatic bowl for lighting fixtures, with parts in section, showing our new design, and

Figure 2 is an inverted plan view of the same.
We claim:

The ornamental design for a combined reflector and prismatic bowl for lighting fixtures, as shown and described.

THOMAS W. ROLPH,
HENRY L. LOGAN.
